United States Patent Office.

PARLEY HOWE, OF STAFFORDVILLE, CONNECTICUT.

Letters Patent No. 64,318, dated April 30, 1867.

IMPROVEMENT IN HAND-SPRING FOR MACHINERY.

The Schedule referred to in these Letters Patent and making part of the same.

TO ALL WHOM IT MAY CONCERN:

Be it known that I, PARLEY HOWE, of Staffordville, in the county of Tolland, and State of Connecticut, have invented a new and improved Hand-Spring for Machinery; and I do hereby declare that the following is a full, clear, and exact description thereof, which will enable others skilled in the art to make and use the same, reference being had to the accompanying drawings, forming part of this specification.

The present invention relates to a hand-spring for the starting and stopping of looms and other machines, which hand-spring is of such a construction and arrangement that it can be operated with the utmost facility, ease, and readiness, as will be obvious from the following detail description of the same, reference being had to the accompanying plate of drawings, in which—

Figure 1 is a front view of the hand-spring showing a portion of one of the end frames of the loom; and Figure 2, a vertical section taken in the plane of the line x x , fig. 1.

Similar letters of reference indicate like parts.

A, in the drawings, represents the lever or arm of the hand-spring, which lever, at its lower end, is hung upon a fulerum at B, between the lugs C of the end frame D, and at its upper is provided with a handle, E, for convenience in operating it, this lever or arm being connected with the driving parts of the loom in the ordinary manner, so that it will serve to start or stop the same according as it is moved either one way or the other. To this lever or arm A, near its lower end, is hung, through a wire loop, F, the loose end of a bent spring, G, that, at its other end, is fixed to the end frame D, toward the upper edge of the same, this spring being provided with a clasp, H, between its loose and fixed ends, that, having a thumb-nut I screwed upon its end passed through the end frame D, allows the tension of the said spring to be regulated at pleasure. The upper portion of the hand-lever A moves and plays in and between the sides of a horizontal guide-arm or bar, J, fixed to the frame D, which arm J, at or near its outer end, is notched, so as to allow the arm, when swung or moved out to that point, to fall into it and becoming thus there locked and held, as it were, the action of the bent spring being not only to throw the lever-arm A into such notch, but also, when disengaged therefrom, to draw it toward the other end of the guide-arm or bar J.

I claim as new, and desire to secure by Letters Patent—

The hand-spring, constructed, arranged, and applied substantially as and for the purpose described.

PARLEY HOWE.
